[73] Assignee: North American Philips Corporation,
New York, N.Y.

[57] CLAIM

The ornamental design for a handle for beauty care appliance or the like, as shown and described.

[] Term: 14 Years

DESCRIPTION

FIG. 1 is a top plan view of a handle for beauty care appliance or the like showing our new design;

FIG. 2 is a bottom plan view thereof;

FIG. 3 is a front elevational view thereof;

FIG. 4 is a rear elevational view thereof; and

FIG. 5 is a right-side elevational view, the left-side elevational view being a mirror image thereof.

The broken line showing of an attachment in FIG. 1 is for illustrative purposes only and forms no part of the claimed design.
